US0D1067880S

(12) **United States Design Patent** (10) **Patent No.:** **US D1,067,880 S**
(45) **Date of Patent:** **** Mar. 25, 2025**

(54) **POWER STRIP**

(71) Applicant: **Yanling Zhang**, Lichuan (CN)

(72) Inventor: **Yanling Zhang**, Lichuan (CN)

(**) Term: **15 Years**

(21) Appl. No.: **29/971,631**

(22) Filed: **Nov. 5, 2024**

(30) **Foreign Application Priority Data**

Oct. 30, 2024 (CN) 202430685678.2

(51) **LOC (15) Cl.** **13-03**

(52) **U.S. Cl.**

USPC **D13/139.8; D13/137.2**

(57) **CLAIM**

The ornamental design for a power strip, as shown and described.

DESCRIPTION

FIG. 1 is a front, right and top perspective view of a power strip, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the power strip that form no part of the claimed design.

1 Claim, 8 Drawing Sheets
